HOLDEN P. BALLOU, OF HARTFORD, CONNECTICUT, ASSIGNOR TO WALTER S. SCHUTZ,
TRUSTEE, OF HARTFORD, CONNECTICUT.

AUTOMATIC PIANO-PLAYER.

1,136,924.

Specification of Letters Patent. Patented Apr. 27, 1915.

Application filed May 9, 1914. Serial No. 837,419.

To all whom it may concern:

Be it known that I, HOLDEN P. BALLOU, a subject of the King of Great Britain, residing at Hartford, in the county of Hartford and State of Connecticut, have invented certain new and useful Improvements in Automatic Piano-Players, of which the following is a specification.

This invention relates to automatic piano-players.

One of the principal objects of the invention is the provision of a piano-player action which can be introduced or removed from a piano as a unit.

Another object of the invention is the provision of a piano-player wherein the parts can be easily and readily assembled and as readily taken from place when occasion requires.

The apparatus comprises other features of novelty and advantage which with the foregoing will be stated at length in the following description wherein I will set forth in detail that one of the several forms of embodiment of the invention which I have selected for illustration in the drawings accompanying and forming part of the present specification, this disclosure being provided to enable those skilled in the art to practice the invention. It will be evident that I do not restrict myself to such showing; I may depart therefrom in several respects within the scope of the invention defined by the claims following said description.

Referring to said drawings: Figure 1 is a horizontal sectional top plan view of a piano equipped with a player involving my invention. Fig. 2 is a front elevation partly in section of said piano and player. Fig. 3 is a vertical section on the line 3—3 of Fig. 2. Fig. 4 is a vertical section of the piano player. Fig. 5 is a front elevation of one end of the piano player with parts in section. Fig. 6 is a detail view partly in section, of a pneumatic and its support. Fig. 7 is a front elevation of the parts shown in the preceding figure. Fig. 8 is a vertical sectional view of the vacuum chest and pneumatics, showing a modified form of the vacuum chest.

Like characters refer to like parts throughout the several views, which it will be seen are on different scales.

I have shown in Figs. 1 and 2 part of the case 2 of a piano of known kind for as

already observed my player is adapted to be mounted in and removed from a piano as a unit. The player has a suitable frame which constitutes a carrier for the various parts thereof; that is the chest, the pneumatics, the roll box and the various other adjuncts which ordinarily go to make up a piano-player. The framework for supporting the various parts may be of any desirable nature, although that represented comprises the end brackets or uprights 3 of duplicate construction, and the cross bar 4 connecting said end brackets or uprights 3. In the present instance the roll-box (denoted in a general way by 5) is supported by the cross bar 4 substantially midway of its length, although not directly sustained thereby. As represented the base of the roll box 5 has attached to its under side the brackets 6, the shanks of which are fastened by screws 8 or otherwise, to the face plate 7 of the cross bar, said screws extending into the wooden body of said cross bar 4 which is disposed between the two uprights or brackets 3. The cross bar 4 has fastened to its ends as by screws 9, the cap plates 10, the outer flat faces of which have a bearing against the flat surfaces 11 at the lower portions of the end brackets 3. Through these face plates or tips 10 the bolts 12 extend, the heads of the bolts being countersunk in the inner sides of said plates or tips while the shanks thereof extend through vertically elongated slots 13 in the lower forward portions of the brackets 3, the threaded portions of the bolts receiving the nuts 14 between which and the adjacent brackets the washers 15 are interposed. From this is will be clear that by loosening the nuts 15 the bar 4 can be raised or lowered for purposes of adjustment or leveling and when the bar is properly positioned the nuts 14 will be set to substantially secure the cross bar 4 in rigid relation with the two end brackets. Between the end brackets 3 a vacuum chest such as that denoted in a general way by 16 may be mounted. This vacuum chest acts to aid in tying the two end brackets together, having on its ends the face plates 17 fastened in position in some suitable manner as by the screws 18. Extending through perforations in the face plates 17 are two sets of bolts 19, the heads of the bolts being countersunk in the inner sides of the plates 17 and the shanks thereof ex-

tending through parallel vertically elongated slots 20 in the two brackets 3 so as to provide for the adjusting or leveling of the chest 16. The threaded portions of the bolts 19 receive the nuts 21 between which and the brackets 3, the washers 22 are disposed and when the chest 16 is correctly located, these nuts 21 are set, so that in effect the chest becomes a part of the frame, acting to substantially aid in maintaining the brackets 3 in proper relation with each other. The chest 16 carries the pneumatics and certain other coöperating parts as will hereinafter more particularly appear. The frame which I have set forth is generally mounted in the upper forward side of the case 2 of the piano in front of the piano action, and it may be removably secured in position in any desirable manner, for instance by the thumb screws 23 which extend through perforations in the feet 24 projecting toward each other, of the respective end brackets 3, these feet in the present instance being adapted to rest upon the rails 25 within the piano, the rails receiving the screws 23 to rigidly hold the player-action in place.

The chest 16 has in it a vacuum chamber 26 which is connected as by the duct 27 with some suitable form of exhaust device (not shown). The upper side of this exhaust or vacuum chamber 26 is preferably transparent glass as 28 in one or more sections answering satisfactorily in this connection, the chest 16 having a ledge 29 on which the glass covering 28 rests and said cover being held in place by the clamping members 30 between which and the glass 28 the packing 31 is disposed. In the roll box 5 is mounted the tracker 32 which may be of any of the usual forms now in use and from which to the chest 16, the ducts 33 lead. The roll box 5 has provision within it for removably supporting the roll or bobbin 34 which carries the sheet 35 which is fed onto the receiving roll 36, the usual motor 37 shown diagrammatically or symbolically being provided to operate the roll mechanism after the customary fashion. The motor 37 it will be noted, is sustained by the cross bar 4. In the chest 16 are the approximately L-shaped passages 38, the vertical portions of which receive the nipples 39 in their upper ends, the perforations of the nipples putting the passages 38 into communication with the vacuum chamber 26 and constituting convenient bleed openings. The forwardly-projecting branches of the passages 38 are extended upward for a short distance and open into the chambers 40 covered by diaphragms 41 having stems 42 connected approximately centrally therewith and rising therefrom. Each stem 42 carries a lower valve 43 and an upper valve 44, the lower valves 43 controlling openings at the lower end of the passages 45 while the upper valves 44 con-

trol openings at the upper ends of said passages 45. The lower portions of the stems 42 extend through the chamber 46 open at its forward side to receive the hand or a suitable implement to provide for ready access to the diaphragms 41 and valves 43, which it will be noted are located in the chamber 46. Access can be had to the upper valves 44 by lifting off the cover plate 28. The passages 45 as will hereinafter appear are operatively connected with the key operating pneumatics. It will be assumed that the exhaust apparatus is in action. In this event there is suction or a vacuum in the chamber 26 which acts on the diaphragms 41 by way of the bleed-openings in the nipples 39, passages 38 and chambers 40 so as to draw said diaphragms downward thereby opening the valves 43 or holding them away from their seats at the lower open ends of the passages 45 and at the same time causing the upper valves 44 to close against their seats at the upper open ends of said passages 45, thereby cutting off the vacuum chamber 26 from the several pneumatics 47.

As shown the pneumatics 47 are arranged in two horizontal rows, those of the upper row being carried by the chest 16, while those of the lower row are connected to the strip 48. The mounting of these pneumatics will be hereinafter more particularly described. As shown the strip 48 has suitably fastened to the upper side of its ends the spacing blocks 49 attached in like manner to the under side of the chest 16, the upper row of pneumatics in the present instance being between the strip 48 and the chest 16, while the lower pneumatics depend from said strip. Extending between the movable boards of the pneumatics and the fingers 50 are the links 51 which are preferably longitudinally adjustable. This adjustment can be obtained by making said links of sectional form and connecting their sections by turn buckles 52. The upper ends of the links are pivoted to the members 53 fastened to the lower boards of the pneumatics 47, while their lower ends are similarly connected to the fingers 50 near the free ends thereof, the butts of said fingers being pivoted to blocks 54 fastened to the upper side of the cross bar 4. As shown the free ends of the fingers 50 act against the wippens 55.

The means for putting the pneumatics 47 into communication with the vacuum chamber 26 comprise preferably metal ducts as 56 which as shown are of practically bowed form and which are removably mounted in place. The upper inturned ends of these bowed ducts 56 extend into upper and lower rows of openings 57 in the forward side of the chest 16 being surrounded by gaskets 58 of rubber or other suitable material, to thus provide airtight joints at such points. The ports 59 connect the upper ends of said

ducts 56 with the passages 45. The lower inturned ends of the ducts or tubes 56 fit in openings 60 in the chest 16 and strip 48 respectively, being surrounded by the gaskets 51 fitted in the openings 60. It will be clear that when desired any one of the several tubes can be easily dismounted by a pull on the same and can be as readily replaced. The tubes are of different lengths, owing to the different locations of the openings which receive their terminals. From the lower open ends of the ducts 56 the ports 62 lead, one series of ports 62 being directly in the chest 16 while the other is in the strip 48. These ports 62 are in constant register with ports 63 in the upper stationary boards of the pneumatics 47. It will be assumed that all the valves 43 are open as shown in Fig. 4; that is the valves in question are supposed to be uncovering the lower ends of the passages 45. As a consequence it follows that the valves 44 are closed or are against their seats at the upper ends of said passages 45, the exhaust device (not shown) in communication with the chamber 26 exhausting air from the latter to maintain this relation. It has been assumed at this time that the holes or openings in the tracker 32 are closed by the imperforate portion of the music sheet 35. When a perforation in the music sheet registers with a tracker hole, this puts the duct 33 connected with said tracker hole into communication with the atmosphere, so that atmospheric air passing along the duct 33 mentioned will enter the corresponding passage 38 and pass from thence into the corresponding auxiliary chamber 40 and break the vacuum therein so that the suction in the chamber 26 will lift the proper valve 44 and through the stem 42 connected therewith the coöperating valve 43 to close the lower end of the appropriate passage 45 and open the upper end of said passage, by virtue of which the main exhaust chamber 26 by way of a duct 56 is put into communication with a pneumatic 47 to collapse said pneumatic and consequently raise the link or rod 51 connected with the movable board thereof and the elevation of the corresponding finger 50 and operation of the wippen 55 against said finger and the sounding of a note corresponding with the perforation in the note or music sheet 35.

As already observed the pneumatics 47 are removably mounted. Their upper boards at the rear are shown provided with hooks 64 which are adapted to engage in seats 65 in the rear of the chest 16 and strip 48 respectively. Said upper boards at their front are provided with lugs 66 which receive the slidable latches 67 adapted to enter seats 68 in the front of the chest 16 and strip 48 respectively. In Figs. 6 and 7 a pneumatic is shown in operative relation which is maintained by the latch 67. To dismount

the pneumatic the sliding latch 67 is withdrawn from its seat or opening 68 following which said pneumatic is pushed rearwardly to disengage the hook 64 from the seat 65. The heads of the latches 67 and 70 adjacent surfaces of the lugs 66 have registering notches 69 and 70 when the latches are in operative position, adapted to receive a suitable implement to facilitate the withdrawal of said latches. 75

Referring now to Fig. 8, the numeral 75 denotes a modified form of vacuum chest. Fitting into this chest are ducts 76 and 77 arranged in sets, the lower ends of said ducts being connected with the upper and 80 lower rows of pneumatics 78 and 79. The upper ends of these ducts 76 and 77 are connected with the vertical passages 80 in the chest 75, the lower ends of said passages opening into the vacuum chamber 81, while 85 the upper ends thereof are adapted to communicate with the atmosphere by way of one or more ports as 90 in the valve seat 91. Connected with the vacuum chamber 81 is a suitable exhaust device. (Not shown). 90 Extending through the passages 80 are stems 82 connected at their lower end with diaphragms 83 covering the chambers 84 connected with passages 85 adapted to be connected by means of suitable ducts (not 95 shown) with the tracker board (not shown). The bleed openings 86 extend from the main vacuum chambers 81 to the passages 85, so that when the music sheet covers the tracker openings the suction in the main chamber 100 81 by way of the bleed openings 86, passages 85 and chambers 84 will draw the diaphragms 83 downward. Each stem 82 carries an upper valve 87 and a lower valve 88, the upper valves controlling communication between the passages 80 and the atmosphere, and the lower valves controlling communication between said passages 80 and the chamber 81. Normally the valves 88 are closed at which time they fit closely 105 against seats in said passages 80. When vacuum in a chamber 84 is broken by communication with the atmosphere through the tracker mechanism, the diaphragm 83 over said chamber 84 is elevated by suction 110 115 thereby opening the valve 88 connected therewith and closing the corresponding valve 87 so as to put the chamber 81 into communication with one of the pneumatics 78 or 79 by way of the ducts 76 or 77. 120

What is known as an atmospheric valve of which one of those numbered 87 is a type is generally made of compressible material; at least the active portion thereof is. This compressible material usually consists of 125 leather which or some equivalent substance becomes in time or from use packed densely, thereby preventing such a valve from properly seating. In such latter event it is customary to open a vacuum or valve chest and 130

adjust the valve or put a new one in its stead. To compensate for wear in a valve of this kind I provide an adjustable seat as 91 for each of the atmospheric valves 87.

5 When any one of these valves becomes packed or worn from use I can compensate for the defect by adjusting the seat 91 therefore inward, said seat for such purpose adjustably fitting in the outer surface of the

10 vacuum chest 75. As shown the seats 91 are threaded into the top of the vacuum chest 75 and each has two ports 90. When a valve 87 is closed it covers these ports;

15 when the valve is opened the ports are uncovered. The seats 91 in addition to acting as such also constitute guides for the respective stems 82, being centrally perforated as at 92 to receive the free ends of said stems 82, all as shown in said Fig. 8.

20 What I claim is:

1. The combination of two end brackets, a vacuum chest supported by and between the end brackets, a bar also supported by and between the end brackets, a roll box supported by the bar, fingers connected with said bar, pneumatics coöperative with the vacuum chest and supported thereby, and operative connections between said pneumatics and fingers.

30 2. The combination of two end brackets, a vacuum chest between the brackets, tying them together and adjustably connected thereto for adjustment longitudinally of said brackets, a bar between said brackets 35 tying them together and adjustably connected with them for adjustment longitudinal thereof, a roll box supported by the bar, fingers mounted upon the bar, and pneumatics sustained by the vacuum chest and operatively connected with said fingers.

35 3. The combination of two end brackets, a vacuum chest between the brackets connecting and tying them together, a bar between the brackets connecting and tying them together, fingers mounted on the bar, and pneumatics supported by the vacuum chest and operatively connected with said fingers.

40 4. The combination of end-brackets, a bar disposed between the end brackets, provided 50 with metal tips equipped with bolts, the end brackets having vertically elongated slots to receive the bolts and thereby provide for vertical adjustment of said cross bar, nuts on the bolts for engaging the brackets to

hold the bar in adjusted position, a vacuum 55 chest provided at its ends with face plates equipped with bolts, the end brackets having vertically elongated slots to receive said bolts to thereby provide for the vertical adjustment of said vacuum chest, and nuts on 60 the last mentioned bolts, for engaging the end brackets to hold the vacuum chest in an adjusted position.

5. The combination of two end brackets, a vacuum chest supported by and between the 65 end brackets, a bar also supported by and between the end brackets, the bar and vacuum chest jointly tying the end brackets together, and a roll box supported by the bar between said bar and the vacuum chest. 70

6. The combination of two end brackets, a vacuum chest supported by and between the end brackets, and connected with said end brackets for adjustment depthwise thereof, a bar also supported by and between said 75 brackets and connected with said brackets for adjustment depthwise thereof, and a roll box supported by the bar between the bar and the vacuum chest.

7. The combination of two end brackets, a 80 vacuum chest supported by and between the end brackets, a bar also supported by and between the end brackets, below the vacuum chest, the vacuum chest and the bar jointly tying together the end brackets, a roll box 85 supported by the bar, fingers mounted on said bar, pneumatics coöperative with the vacuum chest, and operative connections between the pneumatics and the fingers.

8. The combination of two end brackets, a 90 vacuum chest supported by and between the end brackets, a bar also supported by and between the end brackets, the vacuum chest and the bar jointly tying together the brackets and the bar being located below the 95 vacuum chest, a roll box supported by the bar, between the bar and the vacuum chest, fingers mounted upon said bar, pneumatics coöperative with the vacuum chest and supported thereby, and operative connections 100 between said pneumatics and fingers.

In testimony whereof, I affix my signature in presence of two witnesses.
